UNITED STATES PATENT OFFICE.

FRANK T. CABLE, OF NEW SUFFOLK, NEW YORK, ASSIGNOR TO ELECTRIC BOAT COMPANY, A CORPORATION OF NEW JERSEY.

EXHAUST-MUFFLER FOR ENGINES.

SPECIFICATION forming part of Letters Patent No. 738,160, dated September 8, 1903.

Application filed December 30, 1902. Serial No. 137,104. (No model.)

To all whom it may concern:

Be it known that I, FRANK T. CABLE, a citizen of the United States, residing at New Suffolk, in the county of Suffolk and State of New York, have invented certain new and useful Improvements in Exhaust-Mufflers for Engines, of which the following is a specification.

This invention relates, broadly, to means for muffling the exhaust of an engine in order to destroy or mitigate the noise normally produced by the exhaust, and specifically it relates to a submerged muffler for the exhaust of an internal-combustion engine employed for propelling a submarine boat.

The object of the invention is to provide a means for closing the muffler from the interior of the boat in order to prevent the influx of water when the engine is not running. It has been proposed to provide a submerged exhaust-outlet with a check-valve to prevent the influx of water when the engine is running; but the present invention has another and further object in view. There are considerable periods of time when the internal-combustion engines of a submarine boat are not in operation, and during such periods it is very desirable that means shall be provided to close the exhaust outlet or outlets from the inside of the boat, so that it or they may be absolutely water-tight. This invention provides a means for effecting this purpose.

In the accompanying drawings, which illustrate an embodiment of the invention, Figure 1 is a plan view of the muffler as it appears with the main closing-valve or cover-valve removed. Fig. 2 is substantially a longitudinal vertical section at line x^3 in Fig. 1. Fig. 3 is a plan view of the cover-valve detached. Fig. 4 is a side elevation of the muffler on a smaller scale than the principal views. This view shows the mechanism inside the boat for operating the cover-valve. Fig. 5 is a section at x^5 in Fig. 4.

1 is the body or box of the muffler, 2 are the exhaust-inlets to the box, of which four are shown, and 3 designates in Fig. 4 the exhaust-pipes from the engines. 4 is the top or crown plate of the box 1, which latter is divided by suitable partitions into four chambers connected with the respective exhaust-

pipes. Each one of these chambers has, as herein shown, three outlet-apertures 5 in the plate 4, and each outlet is controlled by a suitable check-valve 6, one of which is shown 55 in Fig. 2. As these check-valves may be all alike, the illustration of one will suffice.

Fig. 4 shows how the muffler is mounted on the hull 7 of the spindle-shaped vessel, and it will be by preference so mounted as to be 60 submerged about four inches when the vessel is operating on the surface.

The valves 6 serve to prevent the influx of water at the apertures 5 when the engines are running and the exhaust in full operation; 65 but when these engines are not operating means now to be described closes the entire muffler water-tight.

8 is a large valve in the nature of a cover and which has been called for convenience 70 the "cover-valve." This valve practically covers the entire surface of the plate 4, and its margin rests on a packing-ring 9, set in a channel in the plate 4. Mounted in the plate 4 are two upright guide-pins 10, which play 75 in tubular guides 11, formed integrally, as here shown, on the inner face of the valve. The bores in these guides are closed at the top by screw-plugs 12, and relief-outlets 13 are formed in them for the escape of water 80 that may collect in them. Obviously the valve 8 in its movements up and down will be guided on the pins 10.

For operating the valve 8 from inside of the boat it is provided with a centrally-disposed stem 14, the head 14^a of which is incarcerated in the valve, and this stem passes down through a stuffing-box 15 into the boat, playing through a tubular guide 16 in the muffler-box and a stuffing-box 17. 90

In the boat the forked lower end of the stem 14 is coupled to a lever 18, fulcrumed at 19 to a bracket or fixed part in the boat. In a fork at the other end of the lever 18 is pivoted a nut 20, which runs on a screw 21, that 95 has rotative bearings in a frame 22. This frame is pivotally connected at its upper end to a bracket 23. The screw is rotated by a hand wheel or crank 24.

Fig. 4 shows in full lines the valve 8, seated 100 on the packing 9, so as to exclude water from the outlets 5. Fig. 2 also shows the valve

closed. The dotted lines in Fig. 4 show the valve open and the position of the lever 18 under these circumstances.

There should be a safety-valve 25 in the 5 crown-plate of the valve 8 to relieve the internal pressure in an emergency. This may be any known or suitable form of relief-valve. Figs. 2 and 3 show only the aperture 25^a, in which this valve is set.

10 Having thus described my invention, I claim—

1. An exhaust-muffler for use on a submarine boat, having an outlet for the exhaust-gases provided with an automatic check-valve 15 to prevent the influx of water when the engine is running, and means for closing said outlet water-tight from the interior of the boat.

2. An exhaust-muffler for use on a submarine boat, having a plurality of outlets for the exhaust-gases, a cover-valve which is adapted 20 to close all of said outlets, and means for operating said cover-valve from the interior of the boat.

25 3. An exhaust-muffler for use on a submarine boat, having a plurality of outlets for the

exhaust-gases, each provided with a check-valve, a cover-valve adapted to close all of said outlets, and means for operating said cover-valve to open and close it.

4. An exhaust-muffler for use submerged; having a plurality of outlets for the exhaust-gases, automatic means for checking the inflow of water at said outlets, and hand-operated means for closing all of said outlets 35 water-tight.

5. A boat having mounted on its hull, exteriorly, an exhaust-muffler so disposed as to be normally submerged, said muffler having a plurality of outlets for the exhaust-gases, 40 a check-valve at each of said outlets, and a cover-valve so disposed as to close all of said outlets, and a lever and screw mechanism within the boat for operating said cover-valve.

In witness whereof I have hereunto signed my name, this 22d day of December, 1902, in the presence of two subscribing witnesses.

FRANK T. CABLE.
